UNITED STATES PATENT OFFICE.

JAMES E. HALE, OF AKRON, OHIO, ASSIGNOR TO THE GOODYEAR TIRE & RUBBER COMPANY, OF AKRON, OHIO, A CORPORATION OF OHIO.

DESIGN FOR A TIRE.

52,650.

Specification for Design. Patented Nov. 12, 1918.

Application filed June 11, 1917. Serial No. 174,147. Term of patent 14 years.

To all whom it may concern:

Be it known that I, JAMES E. HALE, a citizen of the United States, residing at Akron, in the county of Summit and State of Ohio, have invented a new, original, and ornamental Design for a Tire, of which the following is a specification, reference being had to the accompanying drawing, forming part thereof.

The figure is a fragmentary view of a tire tread showing my new design.

I claim:

The ornamental design for a tire, as shown:

JAMES E. HALE.

Witnesses:

J. E. KEATING,
R. S. TROGNER.
